UNITED STATES PATENT OFFICE.

SAMUEL HAYWARD, OF BOSTON, MASSACHUSETTS, ASSIGNOR TO J. ESTEY
& COMPANY, OF BRATTLEBOROUGH, VERMONT.

DESIGN FOR AN ORGAN-CASE.

Specification forming part of Design No. 6,511, dated March 18, 1873.

To all whom it may concern:

Be it known that I, SAMUEL HAYWARD, of Boston, in the State of Massachusetts, have invented a Design for an Organ-Case, of which the following is a specification:

The nature of my design is fully represented in the accompanying photographic illustration, to which reference is made.

A represents the body of the case, which, in general shape, is adapted to the form and proportion of a double-bank organ, and is ornamented and enriched by the consoles B on the front corners, by the scrolls C C at the top, and medallions G G' at the sides and front. At each of the angles formed by the intersection of the back and sides a column, D, arises, of polygonal form in cross-section, and having fluted sides, as shown, its base being of corresponding height and style with that of the case, and surmounted at the top, at an elevation above the case, with the head or capital E.

These two columns, standing at the rear of the case, give a bold, substantial, and finished

appearance to the design, and add much to the elegance and richness of the ornate part.

What I claim as my invention is—

1. The design for the columns D D at the rear corners of the case, substantially as herein shown.

2. The designs for the heads E E and columns D D, substantially as herein shown and described.

3. The design for the consoles B B, substantially as herein shown and described.

4. The design for the scrolls C C, as herein shown and described.

5. The design for the medallions G G' at the sides and front, as herein shown and described.

In witness whereof I have hereunto signed my name in the presence of two subscribing witnesses.

SAMUEL HAYWARD.
